ELEVATING PLATFORM

Walter E. Hamlin, Cleveland, Ohio, assignor to
 The Cleveland Shopping News Company,
 Cleveland, Ohio, a corporation of Ohio

Application October 6, 1936, Serial No. 104,236

10 Claims. (Cl. 304—29)

In multiple cylinder printing presses it is necessary for press men to have ready access to cylinders and inking rollers which are at different elevations from the floor. The foot boards are built, as customary, in unchangeable fixture on the framing near certain cylinders and are in the way of others and in general inconvenient in operation of the press. In accordance with the present invention however, a construction is had which affords access readily to cylinders required, as and when necessary, and in a manner simple and convenient. Other features and advantages will appear as the description proceeds.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is a side elevational view of an embodiment of the invention; Fig. 2 is an enlarged fragmentary detail; Fig. 3 is an enlarged fragmentary end elevation; and Figs. 4 and 5 are enlarged sectional details.

Referring more particularly to the drawing, there is shown a multiple cylinder printing press P, with framing 2 and cylinders 3. Mounted at a higher level, and in general parallelism with the axes of the cylinders are horizontal shafts 6. Ordinarily being above the level of the top of the press, these may be carried in bearings 7 (see Fig. 3) on suitable points of support, whether built up extensions from the framing or utilization of ceiling beams 8. Desirably, these are in pairs, and one at least of each pair extends to the floor. Advantageously, steel tubing may be used in the uprights, affording a maximum strength for size and weight. At a lower level, intermediate on the uprights, are lower shafts 11, and on these are carried bearings 12 to which are secured foot planks 13. Advantageously, these may involve plank members 14 framed in by angle irons 15 and T irons 16, thereby increasing strength with lightness. At one or both ends of the foot-way, ladder steps 17 are incorporated on the uprights. Means is provided for raising the uprights and structure carried thereby, and while this may take the form of any suitable raising means, a particularly convenient and effective means is a fluid pressure cylinder 20 having a piston or plunger with its rod 21 carrying on its free end

a sheave 22, while a cable 23 thereabout extends from a point of anchorage 24 (as for instance the adjacent shaft 6), over the sheave 25, which may be mounted on the same shaft, the cable thence extending to a point of attachment 26, which conveniently may be an intermediate lower shaft 11.

By appropriate control of the raising means, the uprights 9 with the foot-way 13 may then be raised to such heights as desired, the fluid pressure piston, drawing its sheave 22, causing the cable to take up, thereby raising the associated structure and swinging the uprights 9 toward the left in Fig. 1, about their upper pivots 6, the foot-way being raised thereby as desired. It may in fact be thus swung clear up against the ceiling or at least high enough to be entirely out of the way, if required. The control of the fluid pressure cylinder 20 may conveniently be a three way valve 30 located at a convenient point of command of the press, and having the connecting pipes 31, 32 extending therefrom to the cylinder 20. A single valve lever 33 with pull chains 34 forms a convenient hand control.

Preferably, the floor-end of each upright 9 which is to rest on the floor, has a roller ball bearing 37, and this may be mounted in a recess in an end foot piece 38, the edges of the recess being sufficiently closed down to prevent escape of the ball. Desirably, the foot piece 38 is telescopingly mounted with respect to the upright 9, and arranged for limited movement with respect thereto, a spring 39 being interposed between an abutment point, such as a pin 40 in the upright, and the upper end of the spring, the lower end of the spring abutting a shoulder 41 on the foot piece 38. The limitation of movement of the foot piece may be provided by pin and slot connection, such as a pin 42 in the foot piece extending into slots 43 in the tubular upright 9. In this manner, the uprights may always properly seat down on the floor when in lowermost position. Side-guards 45 may be located above and parallel to the foot board 13, and chains or cable are convenient for this.

The operation of the mechanism will be clear from the foregoing. If the press men have to work on cylinders at a position above the floor level, they climb on the foot board 13 and work therefrom, the uprights 9 being in their normal position on the floor. If it is desired to raise the foot board higher, the operator pulls the control cord of the valve lever 33, and admits fluid pressure through the pipe 31 to the fluid pressure cylinder 20, and the piston with its sheave 22 pulls

- the cable 23 correspondingly and raises the foot board as desired. If access along the entire side of the press is wanted, and the foot board is not desired at any level, the control cord of the fluid pressure valve is actuated correspondingly, and the cable 23 is drawn up fully, swinging the standards 9 and the foot board up entirely out of the way against the ceiling. When it is desired to lower the standards to normal position on the floor, the valve control cord is pulled to allow the pressure fluid to pass out via the exhaust connection 46, and the sheave 22 allows the standards 9 to swing back down against the floor. Thus, for presses and the like where access is necessary at desired upper levels, effective and convenient arrangement therefor is had, and with the advantage additionally of capability of entire elevation where full access otherwise is desired.
- 20 To guard the piston rod 21 against any slight angular upward or downward dis-aligning pull by the action of the cable and sheave if exactness of linear direction should not be had, a steadyng guide for the travel of the sheave-end of the piston rod is provided. While this may be in the form of guides along on the side or below it is usually more convenient to put the guide above. For instance, a channel rail 50 with inturned flanges 51 may constitute a travel-way for rollers 30 52 whose axle carries a fork 53 on the sheave-end of the piston rod 21.

Other modes of applying the principle of the invention may be employed, change being made as regards the details described, provided the features stated in any of the following claims, or the equivalent of such, be employed.

I therefore particularly point out and distinctly claim as my invention:—

1. In mechanism for providing access to machinery such as printing cylinders and inking rollers, framing comprising a plurality of upper horizontal shafts mounted in bearings at a higher level than said cylinders, tubular uprights depending from said shafts in pairs, one at least of each pair extending to the floor and containing at its floor end a telescopic foot piece with pin and slot connection limiting its range of movement with relation to the tubular upright, a spring setting against the upper end of said telescoping foot piece, and a roller ball bearing on the lower end of said foot piece, lower shafts between pairs of said uprights at an intermediate point in their height, bearings mounted on said shafts, angle and T irons and planks therebetween fastened to said bearings, side-guards extending between the outside uprights at a level above said planks, and means for raising the uprights, including a fluid-pressure cylinder with a plunger and a sheave carried by the free end of the plunger and a cable anchored to one of the upper shafts and extending about said sheave and thence over another sheave on the end upper shaft to a point of attachment on an intermediate lower shaft.

2. In mechanism for providing access to machinery such as printing cylinders and inking rollers, framing comprising a plurality of upper horizontal shafts mounted in bearings at a higher level than said cylinders, tubular uprights depending from said shafts in pairs, one at least of each pair extending to the floor and containing at the floor end a take-up foot piece, lower shafts between pairs of said uprights at an intermediate point in their height, bearings mounted on said shafts, angle and T irons and planks therebetween fastened to said bearings, side-guards ex-

tending between the outside uprights at a level above said planks, and means for raising the uprights, including a fluid-pressure cylinder with a plunger and a sheave carried by the free end of the plunger and a cable anchored to one of the upper shafts and extending about said sheave and thence over another sheave on the end upper shaft to a point of attachment on an intermediate lower shaft.

3. In mechanism for providing access to machinery such as printing cylinders and inking rollers, framing comprising a plurality of upper horizontal shafts mounted in bearings at a higher level than said cylinders, tubular uprights depending from said shafts in pairs, one at least of each pair extending to the floor and containing at its floor end a telescopic foot piece with pin and slot connection limiting its range of movement with relation to the tubular upright, a spring setting against the upper end of said telescoping foot piece, and a roller ball bearing on the lower end of said foot piece, lower shafts between pairs of said uprights at an intermediate point in their height, bearings mounted on said shafts, angle and T irons and planks therebetween fastened to said bearings, and means for raising the uprights, including a fluid-pressure cylinder with a plunger and a sheave carried by the free end of the plunger and a cable anchored to one of the upper shafts and extending about said sheave and thence over another sheave on the end upper shaft to a point of attachment on an intermediate lower shaft.

4. In a mechanism for providing access to machinery such as printing cylinders, framing comprising horizontal shafts mounted at a higher level than said cylinders, uprights depending from said shafts in pairs, one at least of each pair extending to the floor, lower shafts between pairs of said uprights at an intermediate point in their height, bearings mounted on said shafts, a foot board secured to said bearings, and means for raising the uprights, including a fluid-pressure cylinder with a plunger and a sheave carried by the free end of the plunger and a cable extending about said sheave and arranged to draw the uprights.

5. In mechanism of the character described, main framing, and framing movable alongside including uprights in pairs, one at least of each pair extending to the floor and containing at its floor end a telescopic foot piece with pin and slot connection limiting its range of movement with relation to the upright, a spring setting against the upper end of said tubular foot piece and a roller ball bearing on the lower end of said foot piece, lower shafts between pairs of said uprights at an intermediate point in their height, bearings mounted on said shafts, foot planks fastened to said bearings, and means for raising the uprights, including a fluid-pressure cylinder with a plunger and a sheave carried by the free end of the plunger and a cable extending about said sheave and arranged to draw the uprights.

6. In mechanism of the character described, main framing, and framing movable alongside including uprights pivoted at a higher level than said parts, at least a portion of said uprights extending to the floor, self-leveling telescopic foot-piece means thereon, foot boards carried by said uprights at an intermediate height, and means for raising the uprights.

7. In mechanism for providing access to machinery such as printing cylinders, uprights pivotally mounted at a higher level than said cyl-

inders, a foot board carried by said uprights at a level below said cylinders, means for raising the uprights and foot board, and means for maintaining said foot board parallel to the floor in all 5 positions.

8. In mechanism for providing access to machinery such as printing cylinders, uprights in pairs pivotally mounted at a higher level than said cylinders, one at least of each pair extending 10 to the floor, foot board means carried by said uprights at an intermediate point in their height, including angle and T irons and planks therebetween, and fluid-pressure means for raising the uprights.

15 9. In mechanism of the character described, main framing, and framing movable alongside including uprights in pairs, one at least of each pair extending to the floor and having at its lower end a take-up foot piece, foot board means 20 carried by said uprights at an intermediate point in their height, and means for raising the uprights, including a fluid-pressure cylinder with

plunger and a sheave carried by the free end of the plunger and cable extending about said sheave and arranged to draw the uprights, and a channel guide-way with inturned flanges, guide rollers traveling in said channel on said flanges, and a connecting fork between said rollers and the sheave-end of said plunger. 5

10. In mechanism of the character described, main framing, and framing movable alongside including uprights in pairs pivotally mounted at 10 their upper ends and depending toward the floor, foot board means carried at an intermediate point in the height of said uprights, and means for raising the uprights, including a fluid-pressure cylinder with a plunger and a sheave carried by the 15 free end of the plunger and a cable extending by said sheave and arranged to draw the uprights, guide-way means for steadyng the sheave end of the plunger in its travel, and means for maintaining said foot board parallel to the floor in all 20 positions.
